[57] CLAIM

The ornamental design for a vehicle tire, as shown and described.

DESCRIPTION

FIG. 1 is a perspective view of a vehicle tire embodying our new design, it being understood that the pattern is repeated throughout the circumference of the vehicle tire, as shown schematically by solid lines, the opposite side being substantially the same as that shown;
FIG. 2 is a front elevational view of the vehicle tire of FIG. 1 in inverted condition;
FIG. 3 is a side elevational view of the vehicle tire of FIG. 1; and,
FIG. 4 is an enlarged partial front view of the vehicle tire of FIG. 1.
